UNITED STATES PATENT OFFICE

2,655,649

OBJECT LOCATION RELAY SYSTEM

Everard M. Williams, State College, Pa.

Application March 6, 1945, Serial No. 581,264

6 Claims. (Cl. 343—6)

(Granted under Title 35, U. S. Code (1952),
sec. 266)

1

The invention described herein may be manufactured and used by or for the Government for governmental purposes, without the payment to me of any royalty thereon.

This invention relates to a radio system and more particularly to a radio system for the long distance control and direction of an object in flight.

The objects of the present invention comprise the provision of an improved means for the long distance control and direction of an object in flight; an improved device comprising means for relaying to a ground control station, range and azimuth information regarding the position at any desired time of the object in flight; an improved means for imparting substantially accurate information to the ground control station of, and for maintaining from the ground control station control over, the direction, speed and altitude of the object in flight; and a radio remote control system that very largely overcomes jamming interference and that operates at ultra-high frequencies.

With the above and other objects in view which will be apparent to those who are informed in the field of radio controlled objects in flight from the following description, suitable illustrative embodiments of the present invention are shown in the accompanying drawings, wherein:

Fig. 1 is a diagrammatical presentation of the major overall radio elements of the present invention;

Fig. 2 is a diagrammatical presentation of the major overall physical elements of the present invention with the directional and range indicating concept forming parts thereof;

Fig. 3 is a block diagram of a radio circuit in the relay station portion of the present system;

Fig. 4 is a presentation of the radiated pulse envelope that is emitted by the relay circuit that is shown in Fig. 3;

Fig. 5 is a block diagram of a modification in the circuit that is shown in Fig. 3;

Fig. 6 is a partly block diagram and a partly schematic diagram of a circuit at the control station for converting the output of a receiver part of the circuit back to the original azimuth reading;

Fig. 7 is a re-presentation of the signals from a receiver part of the circuit that is shown in Fig. 6;

Fig. 8 is a re-presentation of the flip-flop output signals in the circuit that is shown in Fig. 6;

Fig. 9 is a re-presentation of the mixer output in the circuit that is shown in Fig. 6; and

2

Fig. 10 is a fragmentary modification in the circuit that is shown in Fig. 6.

The overall assembly that is contemplated in the present invention comprises broadly a control station 1, a preferably airborne relay station 2 and an object 3 in flight, such as a missile or the like.

The control station 1 is assumed to remain in a fixed position and is provided with two radar antenna systems, the radar antenna assembly 4 transmitting and receiving signal on a frequency F_1 and the radar antenna assembly 5 receiving signal on a frequency F_2 .

The relay station 2 is preferably supported in the air in any desired manner, as by a balloon 8 that is attached thereto by a tie 9, or the like. The relay station 2 comprises a transpondor beacon 10 on the frequency F_1 and a transpondor beacon 11 on the frequency F_2 that are adapted for being in communication with the control station 1, and with the object 3 in flight. The beacon 10 is preferably provided with two antennas one directed in the general direction of the control station, the other in the general direction of the missile as shown. Alternatively a single omnidirectional antenna may be provided. Similar provision is made for beacon 11.

The object in flight 3 is provided with a receiver 14 operating on the frequency F_1 and an interrogator-transmitter receiver 13 that is operating on the frequency F_2 . The course of the object-in-flight 3 is directed away from both the control station 1 and the relay station 2, as indicated by the arrow 16.

The present system is designed for overcoming the major problem that is encountered in working with long-range guided missiles that have been controlled heretofore by radio signals that have been at the low frequencies necessary for propagation over the required range and that are not adequately accurate and that are easily jammed by interfering radio signals. In the present system a very high frequency, that is substantially of three thousand megacycles, or higher, is used.

In the operation of the present system, a small, lightweight relay station 2 is released preferably from the missile 3 at a desired point between the control station 1, from which the operation is started, and an intended target. The relay station 2 serves to pass back to the control station 1 information regarding the range and azimuth of the missile 3 during its course of flight and also to change the direction of flight, speed and altitude of the missile 3 as dictated by control im-

pulses that are received by the relay station 2 from the ground control station 1.

The missile 3, within a hatch of which the relaying units are releasably disposed, is launched from the ground control station 1 and is initially controlled by a magnetically monitored gyro-compass, and as to its altitude by a barometric altimeter, as are well known in the art.

A parachute, not shown, that carries the relaying units inclusive of the balloon 8 in deflated condition, is released in known manner from the hatch part of the missile 3, at a point determined by an airlog at the ground control station 1. As soon as the parachute-carried relay 2 is cleared by the missile 3, the self-erecting balloon 8 is inflated automatically. The balloon 8 becomes erected and carries the relay station 2 to an altitude that is determined by a preset barometric device in known manner. This altitude preferably is as high as is practicable.

After the release of the relaying units by the missile 3, the missile 3 may be caused to descend automatically to a lower altitude so that it can be placed accurately upon a desired target.

The beacons 10 and 11, carried by the relay station 2, are relatively non-directional but are oriented in azimuth by a magnetic-compass-controlled gyro, not shown, within the relay station 2, in known manner, or disposed vertically for omnidirectional use. The gyro may actually rotate the entire relay station until its aspect gives optimum operation.

Interrogator 13 on missile 3 sends out interrogation pulses at a regular pulse recurrence rate and over a conical scan until, in the process of scanning, it receives the beacon pulse from beacon 11 at the relay station 2. The beacon 11 transponds at a slightly different frequency from that transmitted by the interrogating transmitter 13 so that nothing except beacon 11 will cause a response thereto.

The interrogator 13 homes on the beacon impulse when picked up and switches to a second mode of operation in which the pulse recurrence frequency is unlocked and is arranged so that each outgoing pulse follows directly upon each pulse received from the beacon 11. In this manner the spacing between pulses is twice that corresponding to the range between missile 3 and relay station 2. The transponder pulses are also transmitted from the relay beacon 11 in the other direction and are received at the ground control station 1 and the range between the relay station 2 and the missile 3 is determined from these pulses in known manner.

The scanning dish of interrogator 13 is provided with a magnetic compass comparison device 26 shown in Fig. 3, which provides for the determination of the azimuth bearing of the relay station 2 with respect to the missile 3. This comparison device develops a signal which, in turn, codes the interrogating pulse from the scanner 13. A preferred method of coding the interrogating pulse will be described hereinafter.

The interrogating transmitter 13 will cease to key in its second mode if it fails to receive in usual manner a single beacon pulse from the relay beacon 11. In the event that a beacon pulse from beacon 11 fails to be received by interrogator 13, a time delay occurs and then interrogator 13 is switched back by known means to its first mode of operation or to its regular pulse recurrence rate and if beacon pulses still are not received, after a second time delay, the interrogator 13 returns to scan.

The interrogator 13 uses a usual form of lobe-switching and homes on the beacon impulses from the relay beacon 11 in both the first and the second modes of operation. The dishes of receiver 14 and of the interrogator 13 of the F₁ and the F₂ systems, respectively, on the missile 3 move in synchronism, both being controlled by F₂ system.

The radio receiver 14 of the frequency F₁ is provided on missile 3 for receiving beacon impulses from beacon 10 of the frequency F₁ on relay station 2. Relay beacon 10, of frequency F₁, responds to radar 4 at the ground control station 1. Radar 4 at the control station 1 is used, by means of a pulse recurrence frequency control that is well known to the art, to apply impulses for controlling the flight of the missile 3 through the frequency F₁ beacon 10 on the relay station 2 and receiver 14. This control governs the azimuth, altitude, throttle, dumping, etc. of the missile 3.

In the relay station 2, the F₁ beacon 10 is a standard type beacon that feeds signals to the ground control station 1 and to the missile 3. The signal of the F₁ beacon 10 is coded according to the azimuth code that is received on the F₂ relay beacon 11 from the F₂ transmitter of interrogator 13 on the missile 3. By so operating, the signal on the F₂ beacon supplies azimuth information to the radar receiver 5 at the ground control station 1. By responding to the pulse recurrence rate changes on the F₁ frequency, the signal on the F₂ beacon enables the controls to be applied to the missile 3.

The radar 4 at the control station 1 is lobe-switched for high angle accuracy, transmits on F₁ frequency and receives the response from the relay F₁ beacon 10 on a slightly different frequency so that ordinary echoes do not appear. The dish of the F₂ receiver 5 on the control station 1 is synchronized in position with the dish of the control station radar 4. The F₂ receiver 5 receives azimuth and range information from the relay station 2. The radar 4 at the control station 1 serves to determine the azimuth, elevation and range of the relay station 2 relative to the ground site. The radar 4 also serves to apply control to the missile 3 by means of variations in the pulse recurrence rate of its control signal.

The position of the missile 3 with respect to the ground station 1 is determined by a plotting method using the interrelations among the ground control station 1, the relay station 2 and the missile 3 that are indicated in Fig. 2 of the accompanying drawing and by the usual application of trigonometrical relations that are involved. Radar at the ground control station 1 is used to determine the angles of azimuth and of elevation of the relay station 2 with respect to the control station 1. The angle of azimuth is the azimuth of the relay 2 from the missile 3. The altitude of the missile 3 is controlled by an altimeter therein. The range 1' between the missile 3 and the relay 2 is determined by the interrogator 13 on the missile 3 and is relayed by the means that have been described to the control station 1. The range 2' between the control station 1 and the relay 2 is determined by radar 4 at the control station in the usual way.

A preferred circuit for use in the coding of azimuth readings on a radar pulse emitted from the interrogator 13 on the missile 3 and comprising a part of the present invention is shown in block diagram form in Fig. 3 of the accompanying drawings.

In the system that is contemplated hereby, 75 indication of azimuth is transmitted by a pair of

coded pulses, an initial radar pulse followed in a very short time interval by a follower pulse. The separation of the initial pulse from the follower pulse is equated with the azimuth plus a constant.

In the circuit that is shown in Fig. 3 of the drawings, a trigger 20 causes a modulator 21 to pulse a transmitter 22. Signal from the transmitter 22 is fed through a TR box 23 to a radar antenna 24 and forms the initial pulse referred to above. At the same time the pulse is fed from a terminal *t* on the modulator 21 through a constant short time delay network 25 to an azimuth coder 26. A delay transmission line in the coder 26 is provided with a continuously sliding arm 27 that is geared directly to the dish of the interrogator 13 on the missile 3. The delay transmission azimuth coder 26 is arranged to rotate in such a fashion that the point N thereon corresponds to north on a magnetic compass. The magnetic compass monitors the N point to keep it oriented to the north through the motor 28.

Operatively, when the dish of interrogator 13 points true north, there is no or zero transmission delay introduced between the beginning of the transmission delay line and a pickoff contact X that is geared to the radar dish. The arc between the pickoff contact X and the point N is the angle that is shown in Figs. 2 and 3 of the drawing. As the dish of interrogator 13 rotates in increasing azimuth, an increasing length of the transmission delay line is introduced between the point N and the pickoff contact X. The pulse from the pickoff contact X is delayed more and more and is fed to the modulator 21 and produces the delayed pulse, which is the follower of the pair of pulses referred to above. The follower pulse so produced, with its time relation to the initial pulse, supplies the azimuth code.

A blanking system for the circuit is provided by a small delay line 30 and a flip-flop blanker 31 that are in series between the pickoff contact X on the delay transmission line in the coder 26 and the modulator 21. The blanking system so provided prevents the delayed pulse mentioned above, after travelling through the delay system and the modulator 21 from initiating a still further pulse, and in turn a continuous group of pulses. The delayed pulse, after a slight delay that is introduced by the small delay line 30 network and that is required to allow the transmitter 22 to send the coded pulse, operates the flip-flop blanker 31 circuit. The flip-flop blanker 31 blanks the modulator 21 for a period that is equal to the total transmission time of the delay assembly of which the azimuth coder 26 forms a part.

The interrogator circuit is provided with a mode switch 32 that has automatic operation for changeover and means providing for triggering a next pulse from a received pulse. Since the F₂ beacon 11 on the relay station 2 does not transpond the azimuth pulse, only one pulse is received by the receiver 5 of the control station 1.

The mode switch 32 is a two position switch. At position *a* the mode switch 32 connects in series an oscillator 33 through a receiver 34 to the TR box 23. At position *b* the mode switch 32 connects the trigger 20 in series with the receiver 34 and the TR box 23.

A presentation of the pulse envelope that is emitted from the antenna 24 of the circuit that is shown in Fig. 3, is shown in Fig. 4 of the drawings. It will be noted that the pulse envelope

that is radiated by the circuit in Fig. 3 comprises a square wave of pulsations that are spaced a linear distance that is equal to the sum of a constant and the product of a second constant and the arc between X and N on the delay transmission line of the coder 26.

A modified system for use in relaying azimuth code from the F₂ frequency beacon 11 to the ground control station 1 is shown in Fig. 5 of the drawings. Whereas in the previously described relay station 2, the beacon 11 on frequency F₂ supplies the azimuth code to the F₁ transpondor 10, in the modification here presented the F₂ transpondor transponds the azimuth code on F₂ frequency to the receiver 5 at the ground control station 1. With this arrangement the coded pulse signal from the F₂ transpondor 11 is prevented from causing the F₂ transmitter 13 to repeat the second received pulse as well as the coded pulse that is generated in its own circuits.

In the circuit that is shown in Fig. 5, the components that are common to both Figs. 3 and 5 bear corresponding numerals that are primed in Fig. 5 and not in Fig. 3. In the modified circuit shown in Fig. 5 the flip-flop blanker 31' is connected in series between the terminal *t'* on the modulator 21' and the receiver 34'. In the circuit so modified the first retransmitted pulse blanks the receiver 34' so that the second pulse will arrive at the receiver during the time during which it is blanked and will not cause an additional pulse to be triggered. The other circuit components function substantially as shown in Fig. 3.

35 A circuit for decoding azimuth code in the present invention is shown in Fig. 6 of the accompanying drawings wherein signals that are intercepted by an antenna assembly 36 are fed from a receiver 37 to a gate circuit 38 which feeds 40 the front pulse of the coded pair to the azimuth indicator 39. An angle indicator 40 on the coder 39 is operated by a motor 41. The front pulse of the coded pair is delayed by a time that corresponds to the position of the angle indicator 43 relative to the beginning of the delay transmission line in the azimuth indicator 39. The front pulse of the coded pair then goes to the amplifier 42. The second pulse of the coded pair is fed directly to the amplifier 42 but in reversed polarity as indicated in Fig. 7 of the drawings. Both pulses pass thru the by-passed tube components 43 and 44 to flip-flop circuits 46 and 47 respectively.

Each pulse trips a corresponding flip-flop circuit 46 and 47. The signal output from the positive flip-flop 46 and the negative flip-flop 47 are fed to the amplifiers 48 and 49, respectively, that are connected in push-pull. Signals from the amplifiers 48 and 49 are fed to the grids of the mixers 50 and 51, respectively. The output of the mixers 50 and 51 is equal to the algebraic sum of the outputs from the positive and negative flip-flop circuits 46 and 47, respectively, substantially as presented in Figs. 8 and 9 of the drawings. The resultant pulse is proportional in length to the difference in position of the wiper on the angle indicator 40 and that correct position of the wiper on the indicator 40 which produces a zero pulse. The correct position of the wiper is that at which the delay introduced into the front signal by azimuth indicator 39 equals the delay of the second pulse behind the front pulse.

The pulse from the mixers 50 and 51 is fed to a pulse lengthener 53 and thence to the field of

a generator 55. The pulse may be of either sign and the generator voltage is polarized according to the sign of the pulse. The generator 55 drives the motor 41 which rotates the wiper on the angle indicator 40. In this manner the motor 41 that drives the wiper on the angle indicator 40 receives voltage to rotate the wiper until the net pulse out of the mixers 50 and 51 is zero. The angle indicator 40 then correctly decodes the azimuth indication of the double pulse signal.

The flip-flop circuits 46 and 47 do not return to their normal state until the timer circuit 56 supplies an impulse. The flip-flop circuits 46 and 47 then return to zero output after a time that is determined by a delay line 57 which feeds the timing circuit 56 from the gate 38 and termination 58 of the azimuth indicator or coder 39.

The system that is here considered may be disposed at the site of the ground control station 1 or can be used in the relay station 2 to decode the F_2 frequency.

Where the system is positioned at the relay station 2, a second delay line 57' and angle indicator slider 40' would be provided to code the pulses of the F_1 frequency beacon, as shown in fragmentary circuit form in Fig. 10 of the drawings. The circuit components that correspond to the circuit components that are shown in Fig. 6 are primed in Fig. 10 for ease of association therewith. In this adaptation the sliding arm 40' applies the signal F_1 , as delayed by the delay line 57' to the amplifier 42', and the sliding arm 40'' applies the signal F_2 , as delayed by the delay line 57'' to the same amplifier 42'. In other component details and for the completion thereof, the circuit that is shown in Fig. 10 comprises and functions substantially as that shown in Fig. 6.

It is to be understood that the system and the circuits and components that have been disclosed and described herein have been submitted for the purposes of illustrating and describing suitably operating embodiments of the present invention and that similarly functioning modifications, alterations, changes and substitutions may be made therein without departing from the scope of the present invention as defined by the appended claims.

What I claim is:

1. A radio system of the character described, comprising in combination a control station, a missile adapted for independent flight, a relay station that is separable from said missile and together therewith adapted for being launched from the site of said control station, and means at said control station for directing thru said relay station the course of flight of said missile after being separated from said relay station.

2. A radio system of the character described, comprising in combination a control station, a missile adapted for independent flight, a relay station that is separable from said missile, means for maintaining said relay station supported in the air after the separation of the missile therefrom, and means operable from said control station for directing the flight path of said missile.

3. A radio system of the character described, comprising in combination a control station, a pair of radar antenna systems at said control station, an airborne relay station, a missile separable from said relay station, means for supporting said relay station, a transpondor beacon on frequency F_1 at said relay station and adapted

for maintaining communication with both said control station and said missile, a transpondor beacon on frequency F_2 at said relay station and adapted for maintaining communication with both said control station and said missile, a receiver on frequency F_1 on said missile for communication thru said relay station with one of said radar antenna systems at said control station, and an interrogator on frequency F_2 on said missile for communication thru said relay station with one of said radar antenna systems at said control station.

4. A radio system of the character described, comprising in combination a control station, a relay station carrying missile controllable in flight from said control station and adapted for liberating the relay station therefrom in flight, means for supporting said relay station, and a radio circuit in said relay station reporting to and controlling from said control station the position and course of flight of the missile subsequent to its separation from said relay station.

5. A radio system for the remote control of an object in flight comprising in combination a control station, a relay station, and an object adapted for independent flight after its separation from said relay station, a radar on frequency F_1 at said control station, a receiver on frequency F_2 at the control station, a receiver on frequency F_1 at the object, an interrogator on frequency F_2 at the object, a relay station carried beacon on frequency F_1 for maintaining signal with the control station radar and the object receiver, and a relay station carried beacon on frequency F_2 for maintaining signal with the control station receiver and the object interrogator.

6. A remote control radar system comprising in combination a ground station, an airborne relay radar station, means at said ground station for determining the location of said airborne relay radar station with respect to said ground station, a self propelled airborne object, instrumentalities at said airborne relay radar station for determining the location of said object with respect to said airborne relay radar station and for transmitting said location to said ground station, and means at said ground station for combining an indication of the location of said object as transmitted from said airborne relay radar station with signals from said location determining means corresponding to the determined location of said airborne relay radar station to derive therefrom the location of said object with reference to said ground station.

EVERARD M. WILLIAMS.
